DESIGN FOR A DRAFTING INSTRUMENT

John A. Truhon, Detroit, Mich.

Application August 14, 1942, Serial No. 107,936

Term of patent 14 years

To all whom it may concern:

Be it known that I, John A. Truhon, a citizen of the United States, residing at 7412 Churchill Avenue, Detroit, Wayne County, Michigan, have invented a new, original, and ornamental Design for a Drafting Instrument, of which the following is a specification, reference being had to the accompanying drawing, forming a part thereof, wherein:

Fig. 1 is a plan view of a drafting instrument, showing my new design; and,

Fig. 2 is a side elevational view of the drawing instrument shown in Fig. 1.

I claim:

The ornamental design for a drafting instrument as shown.

JOHN A. TRUHON.
